(57) **CLAIM**

The ornamental design for a foldable walking aid apparatus, as shown and described.

DESCRIPTION

Fig. 1.1 is a perspective view of a foldable walking aid apparatus in an unfolded, deployed configuration;

Fig. 1.2 is a front view thereof;
Fig. 1.3 is a back view thereof;
Fig. 1.4 is a left view thereof;
Fig. 1.5 is a right view thereof;
Fig. 1.6 is a top view thereof;
Fig. 1.7 is a bottom view thereof;
Fig. 1.8 is a perspective view of the foldable walking aid apparatus of Fig. 1.1 shown in a folded configuration;
Fig. 1.9 is a front view thereof;
Fig. 1.10 is a left view thereof;
Fig. 2.1 is a perspective view of a second embodiment of a foldable walking aid apparatus in an unfolded, deployed configuration;
Fig. 2.2 is a front view thereof;
Fig. 2.3 is a back view thereof;
Fig. 2.4 is a left view thereof;
Fig. 2.5 is a right view thereof;
Fig. 2.6 is a top view thereof;
Fig. 2.7 is a bottom view thereof;
Fig. 2.8 is a perspective view of the foldable walking aid apparatus of Fig. 2.1 shown in a folded configuration;
Fig. 2.9 is a front view thereof;
Fig. 2.10 is a left view thereof;
Fig. 3.1 is a perspective view of a third embodiment of a foldable walking aid apparatus in an unfolded, deployed configuration;
Fig. 3.2 is a front view thereof;
Fig. 3.3 is a back view thereof;
Fig. 3.4 is a left view thereof;
Fig. 3.5 is a right view thereof;
Fig. 3.6 is a top view thereof;
Fig. 3.7 is a bottom view thereof;
Fig. 3.8 is a perspective view of the foldable walking aid apparatus of Fig. 3.1 shown in a folded configuration;
Fig. 3.9 is a front view thereof;
Fig. 3.10 is a left view thereof;
Fig. 4.1 is a perspective view of a fourth embodiment of a foldable walking aid apparatus in an unfolded, deployed configuration;
Fig. 4.2 is a front view thereof;
Fig. 4.3 is a back view thereof;
Fig. 4.4 is a left view thereof;
Fig. 4.5 is a right view thereof;
Fig. 4.6 is a top view thereof;
Fig. 4.7 is a bottom view thereof;
Fig. 4.8 is a perspective view of the foldable walking aid apparatus of Fig. 4.1 shown in a folded configuration;

(Continued)

Fig. 4.9 is a front view thereof;
Fig. 4.10 is a left view thereof.

In all views cables connecting brake handles to associated brake pad arrangements of the foldable walking aid apparatus are not shown and therefore form no part of the claimed design.
